UNITED STATES PATENT OFFICE.

CORNIELOUS J. MACCLAIN, OF HATTON, OHIO.

DETACHABLE SAW-HANDLE.

SPECIFICATION forming part of Letters Patent No. 673,276, dated April 30, 1901.

Application filed February 14, 1901. Serial No. 47,346. (No model.)

To all whom it may concern:

Be it known that I, CORNIELOUS J. MACCLAIN, a citizen of the United States, residing at Hatton, in the county of Wood and State of Ohio, have invented new and useful Improvements in Detachable Saw-Handles, of which the following is a specification.

My invention relates to improvements in that class of saw-handles which are constructed with a view of adapting them to be readily connected to and disconnected from saw-blades, and has for its general object to provide a detachable saw-handle which, in addition to being susceptible of ready application to and removal from a saw-blade, is calculated to lend rigidity to the blade and lessen the liability of the same being twisted or broken in practice.

With the foregoing in mind the invention will be fully understood from the following description and claims when taken in connection with the accompanying drawings, in which—

Figure 1 is a broken elevation of my improved handle connected to a saw-blade. Fig. 2 is an enlarged horizontal section taken in the plane indicated by the broken line 2 2 of Fig. 1 looking in the direction indicated by arrow. Fig. 3 is a vertical section taken 30 through the longitudinal center of the handle and illustrating the adjustable gage-plate thereof. Fig. 4 is a transverse section taken in the plane indicated by the broken line 4 4 of Fig. 1 looking in the direction indicated by arrow.

In the said drawings similar letters of reference designate corresponding parts in all of the views, referring to which—

A is a saw-blade having an aperture a adjacent to its end.

B is the body or main portion of my improved handle, which is preferably of malleable iron, and C is the grasp of the handle, which is preferably of wood. The body or main portion B in the preferred embodiment of the invention is formed of a single piece of metal bent so as to comprise an eye or loop b for the reception of the reduced portion of the grasp C and parallel plates c d, the former of which is provided at its forward end with a portion c' of increased thickness, in which is formed a longitudinally-disposed threaded socket c'.

This socket is designed to receive the threaded shank of a tongue e, bent, as shown, and adapted to be passed through the aperture a 55 of the blade and engage said blade after the manner best illustrated in Fig. 2. The said independent tongue is advantageous because it may be formed of steel, while the body B is formed of malleable iron or other cheap 60 metal, and also because it is adapted to be adjusted to accommodate itself to apertures located at different distances from the ends of saw-blades.

The plate d of body B is provided with an 65 outwardly-pressed or offset longitudinal portion f, in which is formed a longitudinal slot g. Said offset or outwardly-pressed portion f is designed to receive a coiled spring h, which is interposed between it and the plate 70 c and bears at one end against a shoulder i at the outer end of the portion f. At its opposite end the spring h bears against the end of a sliding bolt J, which it serves to normally hold in the position shown in Fig. 2— 75 that is to say, extended beyond the end of the plate d, so as to rest at the opposite side of a saw-blade with reference to the portion of the tongue e adjacent to the plate c. Bolt J is provided with a finger-piece j, through 80 the medium of which it may be readily retracted against the action of spring h to draw it out of engagement with the saw-blade and permit of the handle being disconnected from said blade.

D is a gage-plate which is slotted at k to accommodate the spring h and is also slotted, as indicated by l, to receive the transverse bolts m, which connect the plates c and d of the body B. By reason of this construction 90 it will be observed that the plate D, which has a square forward end n, adapted to bear against the end of the saw-blade, may be readily adjusted and adjustably fixed to adapt the handle for application to different saws— 95 that is to say, saw-blades the apertures of which are arranged at different distances from the ends thereof.

I do not desire to be understood as confining myself to an adjustable tongue, as it might 100 be formed integral with the plate c of body B without departing from the scope of my claims.

In order to remove my improved handle

from a saw-blade, it is simply necessary to retract the bolt J until it clears the end of the blade, when by moving the handle to a position at an angle to the blade the tongue 5 e may be readily withdrawn from the aperture of said blade. To connect the handle to the blade, it is simply necessary to reverse the operation described—*i. e.*, to insert or pass the bent portion of the tongue through the 10 aperture of the blade while the handle is held at an angle to the blade and then move the handle into a position in alinement with the blade and release the bolt J and permit it to assume a position at the opposite side of the 15 blade with respect to the portion of the tongue adjacent to the plate c. When the handle is thus applied, it will be seen that the blade bears at one end against the gage-plate D and rests between the bolt J and a portion of 20 the tongue e adjacent to plate c. By virtue of this rigidity and strength is lent the blade and liability of the same being broken or twisted in practice is reduced to a minimum.

It will be appreciated from the foregoing 25 that my improved handle is simple and durable in construction, and in addition to being susceptible of ready and secure connection to and disconnection from a saw-blade is calculated to add to the strength and period of 30 usefulness of the saw-blade. I have entered into a detail description of the present embodiment of my invention in order to impart a full, clear, and exact understanding of the same. I do not desire, however, to be understood as confining myself to such specific 35 construction and arrangement of parts, as such changes or modifications may be made in practice as fairly fall within the scope of my invention.

40 Having described my invention, what I claim, and desire to secure by Letters Patent, is—

1. A detachable saw-handle comprising a body provided with a tongue adapted to rest 45 at one side of a saw-blade and terminating in a bent portion adapted to be passed through an aperture in the blade and engage the opposite side thereof, and a spring-backed bolt arranged in the body and adapted, in its normal 50 position, to rest at the opposite side of the blade, with reference to the main portion of the tongue.

2. A detachable saw-handle comprising a

body provided with a tongue adapted to rest at one side of a saw-blade and terminating in 55 a bent portion adapted to be passed through an aperture in the blade and engage the opposite side thereof, a spring-backed bolt arranged in the body and adapted, in its normal position, to rest at the opposite side of 60 the blade, with reference to the main portion of the tongue, and a gage adjustably fixed in the body and adapted to bear against the end of the saw-blade.

3. A detachable saw-handle comprising a 65 metallic body having the loop or eye to receive the grasp, a side portion terminating in a tongue provided with a bent portion, a side portion or plate having an offset and a slot therein, bolts connecting the side plates 70 or portions, a bolt having a finger-piece extending through the slot in one side plate of the body, a spring occupying the offset in said side plate, and backing the bolt, and a gage-plate interposed between the side plates 75 or portions of the body and having slots receiving the connecting-bolts thereof.

4. A detachable saw-handle comprising a body having a threaded socket, a threaded tongue adjustable in said socket and adapted 80 to rest at one side of a saw-blade and terminating in a bent portion adapted to be passed through an aperture in the blade and engage the opposite side thereof, and means carried by the body and arranged to rest at the opposite side of the blade with reference to the main portion of the tongue.

5. A detachable saw-handle comprising a body having a threaded socket, a threaded tongue adjustable in said socket and adapted 90 to rest at one side of a saw-blade and terminating in a bent portion adapted to be passed through an aperture in the blade and engage the opposite side thereof, means carried by the body and arranged to rest at the opposite side of the blade with reference to the main portion of the tongue, and a gage adjustably fixed in the body and adapted to abut against the end of the saw-blade.

In testimony whereof I have hereunto set 100 my hand in presence of two subscribing witnesses.

CORNIELOUS J. MACCLAIN.
